SEBRING I. PHELPS, OF WILMETTE, ILLINOIS.

HIGH-TEMPERATURE ELECTRIC HEATER.

1,402,376.

Specification of Letters Patent. Patented Jan. 3, 1922.

Application filed February 20, 1919. Serial No. 278,119.

To all whom it may concern:

Be it known that I, SEBRING I. PHELPS, a citizen of the United States of America, and a resident of Wilmette, county of Cook, 5 and State of Illinois, have invented certain new and useful Improvements in High-Temperature Electric Heaters, of which the following is a specification.

This invention relates to high-temperature electric heaters, particularly those 10 adapted for kitchens use. The greatest trouble experienced with electric heating units or burners built to secure sufficient heat for frying and boiling foods has been 15 and is the frequency of renewals of the resistance ribbons or wire, caused by fusing or disintegration of the resistance when operated at the necessary temperature to compete with flame stove heat. 20 It is also necessary to build up this high-temperature within a diameter or square of 8 inches or less, in order to accommodate the ordinary cooking utensils, most of which are of a diameter less than 8 inches, except 25 perhaps some frying pans and teakettles.

There are listed for sale electric heating units or burners, commonly called hotplates, of 10 and 12 inches diameter, which are claimed to operate at as high as 2000 watts, 30 but none as small as 8 inches are claimed to operate at more than 1500 watts.

The life or durability of heating units or hotplates is very uncertain even on intermittent use, making the cost of renewals of 35 the resistance expensive and annoying, and even 1500 watts in an 8-inch diameter does not contain sufficient heat units to compete successfully in speed and service with gas or flame heat in corresponding or smaller 40 diameters, and where such large burners or hotplates as 10 inches are used to secure 1800 or 2000 watts, no efficiency or economy is secured if a utensil of but seven or eight inches diameter is being used, as the extra 45 exposed surface dissipates electric heat at a loss.

The main objects of this invention are to provide a stove or heater of improved form adapted for greater concentration of heat 50 without injury to the generating elements, so as to compete and compare favorably with flame stove heat and at the same time eliminate or greatly reduce the usual necessary frequent renewals of the heat-generating elements; to provide an improved form

and arrangement of heater elements or parts and protective means therefor; to provide improved means for conducting the heat generated in a remote part of the generator circuit to a limited area or point of heat 60 application; and to provide for an assemblage of heat generators and good heat conductors adapted and arranged to deliver a powerful concentration of heat to a limited area of application. 65

An illustrative embodiment of this invention is shown in the accompanying drawings, in which—

Fig. 1 is a top plan of the heater assembled complete. 70

Fig. 2 is a section on the line 2—2 of Fig. 1. 75

Fig. 3 is a front elevation of the heater with the medial part of the front wall broken away to show the interior.

Fig. 4 is an enlarged vertical sectional detail of one of the heater units. 75

Fig. 5 is an end view of an upper corner of one of the units.

Fig. 6 is a top view of one end of one of 80 the units.

Fig. 7 shows a modification.

In the construction shown in the drawings, the heater comprises mainly a frame 1, a plurality of heater units or elements 2. 85

Said frame 1, for convenience in manufacture and for commercial reasons, is preferably rectangular in plan. The body part of the frame is of sufficient height to accommodate the thin heater plates 2 arranged 90 uprightly side by side, said body part being supported well above the table or other support, not shown, by means of the frame legs 5 formed integrally within the frame.

Each heater unit 2 comprises, in combination, a central core 6 of refractory material such as mica, asbestos, or the like in sheet form, a heat-generating conductor 7 wound thereon, a pair of metallic heat-conducting armor plates 8 and 9, and a pair of insulator 100 plates 10. The plates 8 and 9 are disposed on opposite sides of said plate 6 and insulated from the resistance 7 by the refractory sheets 10. The plates 8 and 9 are tightly clamped together and serve to conduct the 105 heat rapidly away from said generating wire and transmit it to the top of the heater where the plate-edges lie in substantially the same plane. The upper edge of each unit is provided with a horizontal flange 11 inte- 110

gral with one of the heat conductors, for instance plate 8, which provides for more surface contact between the heat-generating units and the utensils so as to more efficiently 5 transmit and distribute the heat to the utensil or other object placed on or above the heater.

In order that different degrees of heat may be readily obtained from the same 10 heater, a switch commonly known as a "three heat switch" is arranged on the frame and connected in a suitable manner with the several units.

Each plate 8 is provided with an end 15 tension or lug 25 at or near its upper edge adapted to fit in a corresponding vertical slot 26 in the frame bar 27. Just below said lug 25 a narrow strip 28 is provided adapted to fold over the opposite plate 9 for binding 20 the plates together. The lower portion of the unit is also held together by a finger 29 formed on one of the plates 8 and 9 and folded around the other.

In order to concentrate the air draft and 25 application of heat generally to the usual area represented by an ordinary cooking utensil, as for instance, a frying pan or the like, a removable centrally apertured top or cover member 30 is provided. Said top is 30 made of very thin sheet metal and has a circular hole. It is provided with a downward outer flange 32 adapted to fit over the top of frame 1 and over the end lugs 25.

The frame is preferably enclosed on all 35 sides, but may be left open at the bottom so as to admit an upward draft of air, which, becoming highly heated, transmits heat effectually to any object on the heater.

There are numerous ways in which the device 40 as a whole may be wired. A suitable switch (not shown) is connected by leads to central binding posts or fasteners 22', 23', and 24'. From post 22' a plurality of distributing leads 35 extend to corresponding 45 fasteners 36 secured to one side of the frame. Other leads 37 and 38 extend from posts 23' and 24' to fasteners 39 and 40 respectively secured to the opposite side of the frame. Each element 2 has one of its terminal leads 50 secured to one of the posts 36 and the other to one of the posts 39 or 40. Cross bars 42 extend across the bottom and support the terminals 22', 23', and 24' which are mounted thereon.

The operation of the device is controlled 55 by the switch which may be thrown to one or the other of its positions to give either a "low" heat, "medium" heat or "high" heat, depending upon the purpose for which the device is to be used.

Plain heat-conducting plates 45 may to advantage be disposed alternately with the generating units 2, as shown in Fig. 8, especially if the generator be made relatively

deep. In this instance, heat radiating from 65 the lower portion of a unit 2 is absorbed and transmitted upward by the plates 45 and delivered through its flanged upper edge to the utensil or other object to be heated. By this means, it is practical to maintain a sufficient temperature at the point or surface of application, with a lower excess degree of heat at the point of generation, and thereby avoid the burn-outs that occur at the higher temperatures. 70

In order to demonstrate my invention and to show that it is practicable to reduce the necessity of frequent renewals and to secure a very much higher heat than obtained heretofore in such devices, I have designed and 80 fully tested this method of securing from 1000 to 1500 watts in a 6-inch, 2000 to 3000 watts in an 8-inch, and 3000 to 4000 watts in a 10-inch square heater.

Briefly summarized, my method consists 85 in winding on a flat surface of insulation material, flat ribbon or other resistance material so that each winding forms a complete unit operating at a low temperature in itself. By spacing closely together a multiple of 90 these low-temperature units, I secure a very high generating capacity and efficient temperature, within an economic operating space.

I have used these units in multiple, at 95 about 250 watts each, hanging or supported vertically, rather than horizontally as has been the common practice in the use of flat resistance or coil resistance, and am securing temperatures from 33 $\frac{1}{2}$ to 100% greater 100 than have heretofore been secured, to my knowledge, within so small diameters or squares as 6 to 8 inches.

By making use of heat conductivity and radiation in arranging this device, I gain a 105 large efficiency over those units where radiation only is secured. A decided advantage is secured by the use of these low-temperature units, for each unit may be inserted or taken from its position without disturbing 110 any other unit or even throwing off the current. If any one unit should fuse, it would do so within itself, and the "hotplate" or "burner" has lost but a very small part of its efficiency, even if no new unit were immediately inserted.

The units are instantly interchangeable, and it is both possible and practical to take an 8-inch frame, for example, and insert enough units to make, say, 1000 watts, or to 120 insert enough to make 1500, 2000, 2500, or 3000, or if it is a 3000-watt unit, enough units can be removed (even while the electric current is on) to reduce the wattage and temperature accordingly, to any practical 125 wattage desired.

Another advantage, and this is a great advantage, is due to the fact that the volt-

age in the same central station varies, sometimes as much as 10 volts during the day and night service.

Heretofore, electric burners or hotplates have been and are commonly wound for a voltage fluctuation of but 2 to 4 volts. With this new burner or hotplate (units in multiple) the low temperature of each unit in the multiple will permit a voltage fluctuation of 25 volts without danger of fusing the winding (resistance), yet give very high efficiency even if the voltage should "drop" instead of advance, and it usually drops more frequently than it advances over the normal voltage.

Although but two specific embodiments of this invention are herein shown and described, it will be understood that other embodiments are possible, and numerous details of the constructions shown may be altered or omitted, without departing from the spirit of this invention as defined by the following claims.

I claim:

- 25 1. A culinary electric heater comprising a frame, a plurality of separately constructed heating units arranged side by side on said frame so that they all have one face or edge thereof disposed in substantially the same horizontal plane, thereby forming a support upon which a culinary utensil may rest with the bottom thereof in direct contact with each of said units, each of said heating units including a resistance winding constructed to operate at a comparatively low wattage, and electric conductors on said frame connecting all of said units in parallel with each other, and with a source of electricity.
- 30 2. A culinary electric heater comprising a frame, a plurality of separately constructed heating units each of flat rectangular shape arranged side by side on said frame in vertically spaced relation so that they all have
- 35 one edge disposed in substantially the same horizontal plane, thereby forming a support upon which a culinary utensil may rest with the bottom thereof in direct contact with each of said units, each of said heating units including a resistance winding constructed to operate at a comparatively low wattage, and electric conductors on said frame connecting all of said units in parallel with each other, and with a source of electricity.
- 40 3. A culinary electric heater comprising a frame, a plurality of separately wound heating units each of flat rectangular shape arranged side by side on said frame in vertically spaced relation so that they all have
- 45 one edge disposed in substantially the same horizontal plane, thereby forming a support upon which a culinary utensil may rest with the bottom thereof in direct contact with each of said units, each of said heating units including a resistance winding constructed to operate at a comparatively low wattage, and electric conductors on said

frame connecting all of said units in parallel with each other and with a source of electricity.

3. A culinary electric heater comprising a frame, a plurality of separately constructed heating units each of flat rectangular shape arranged side by side on said frame in vertically spaced relation so that they all have 60 one edge disposed in substantially the same horizontal plane thereby forming a support upon which a culinary utensil may rest with the bottom thereof in direct contact with each of said units, each of said units 65 including a resistance winding constructed so as to operate at a wattage lower than that which of itself would heat the resistance winding to a state of incandescency, and electric conductors on said frame connecting all of said units in parallel with each other and with a source of electricity. 70

4. An electric heater, comprising a frame, a plurality of separately formed heat-generating units, said frame having notches formed in opposite sides thereof, and shoulders on the ends of said units adapted to engage the respective notches for supporting said units in vertically disposed relation on said frame. 75

5. In an electric heater, the combination of a frame, a plurality of heat-generating units each comprising a flat core member wound with a resistance material and housed between a pair of metal plates rigidly secured together, and coating means on said frame and each of said units for supporting said units vertically in spaced relation on said frame, one of the plates of each of said units having a transversely disposed flange formed on the upper end thereof, and means for supporting said units in vertical spaced relation on said frame whereby said flanges are disposed in substantially the same horizontal plane. 85 90 95

6. In an electric heater of the character described, a combination of a frame, a plurality of heat-generating resistance conductors vertically arranged on said frame, and a plurality of heat conductors interspersed with said resistance conductors. 100

Signed at Chicago this 15th day of Feb., 1919.

SEBRING I. PHELPS.
